[57] CLAIM

The ornamental design for a cushion for use in hunting, as shown and described.

DESCRIPTION

FIG. 1 is a view showing the cushion for use in hunting folded into a seat configuration;

FIG. 2 shows the cushion in a flattened mat configuration; FIG. 3 is an end elevational view of a cushion in its flattened condition;

FIG. 4 is an end elevational view of the opposite end of the cushion in its flattened condition;

FIG. 5 is a top plan view of the cushion in its flattened condition;

FIG. 6 is a bottom plan view of the cushion in its flattened condition;

FIG. 7 is a side elevational view of the cushion in its flattened condition; and,

FIG. 8 is an elevational view of the opposite side of the cushion in its flattened condition.
